UNITED STATES PATENT OFFICE.

WILLIAM B. RIKARD, OF PROSPERITY, SOUTH CAROLINA.

DESIGN FOR A CLOCK-CASE.

44,670.

Specification for Design.

Patented Sept. 16, 1913.

Application filed July 5, 1913. Serial No. 777,593. Term of patent 14 years.

To all whom it may concern:

Be it known that I, WILLIAM B. RIKARD, a citizen of the United States, residing at Prosperity, in the county of Newberry and State of South Carolina, have invented a new, original, and ornamental Design for Clock-Cases, of which the following is a specification, reference being had to the accompanying drawing, forming part thereof.

The figure is an elevation of a clock case showing my new design.

I claim:

The ornamental design for a clock case as shown.

WILLIAM B. RIKARD.

Witnesses:

S. L. FELLOW,
G. W. CROMER.

Copies of this patent may be obtained for five cents each, by addressing the "Commissioner of Patents, Washington, D. C."

Correction in Design Letters Patent No.
44,670.

It is hereby certified that in Letters Patent No. 44,670, granted September 16, 1913, upon the application of William B. Rikard, of Prosperity, South Carolina, for a "Design for a Clock-Case," an error appears in the printed specification requiring correction as follows: The name of the first-mentioned witness to the signature of the patentee for "S. L. Fellow" read S. L. Fellers; and that the said Letters Patent should be read with this correction therein that the same may conform to the record of the case in the Patent Office.

Signed and sealed this 7th day of October, A. D., 1913.
